CLAIM

The ornamental design for a power adapter, as shown and described.

DESCRIPTION

FIG. 1 is top perspective view of a first embodiment of a power adapter showing our new design;

FIG. 2 is a bottom perspective view of thereof;

FIG. 3 is a top plan view thereof;

FIG. 4 is a front elevation view thereof;

FIG. 5 is a rear elevation view thereof;

FIG. 6 is a bottom plan view thereof;

FIG. 7 is a right side elevation view thereof;

FIG. 8 is a left side elevation view thereof;

FIG. 9 is top perspective view of a second embodiment of a power adapter showing our new design;

FIG. 10 is a bottom perspective view of thereof;

FIG. 11 is a top plan view thereof;

FIG. 12 is a front elevation view thereof;

FIG. 13 is a rear elevation view thereof;

FIG. 14 is a bottom plan view thereof;

FIG. 15 is a right side elevation view thereof;

FIG. 16 is a left side elevation view thereof;

FIG. 17 is top perspective view of a third embodiment of a power adapter showing our new design;

FIG. 18 is a bottom perspective view of thereof;

FIG. 19 is a top plan view thereof;

FIG. 20 is a front elevation view thereof;

FIG. 21 is a rear elevation view thereof;

FIG. 22 is a bottom plan view thereof;

FIG. 23 is a right side elevation view thereof; and,

FIG. 24 is a left side elevation view thereof.

The broken lines showing are for illustrative purposes and form no part of the claimed design.
